UNITED STATES PATENT OFFICE.

ALBERT L. HARVEY, OF WILKINSBURG, PENNSYLVANIA, ASSIGNOR TO WESTINGHOUSE ELECTRIC & MANUFACTURING COMPANY, A CORPORATION OF PENNSYLVANIA.

CONTROL SYSTEM.

1,425,647.

Specification of Letters Patent. Patented Aug. 15, 1922.

Application filed May 15, 1919. Serial No. 297,357.

To all whom it may concern:

Be it known that I, ALBERT L. HARVEY, a citizen of the United States, and a resident of Wilkinsburg, in the county of Allegheny and State of Pennsylvania, have invented a new and useful Improvement in Control Systems, of which the following is a specification.

My invention relates to motor-control systems and particularly to systems for controlling shunt and compound-wound direct-current motors that are provided with means for dynamic braking.

The object of my invention is to provide an improved system for controlling the shunt-field excitation of motors of the above-designated character.

In a system arranged according to my invention, the resistor that is in series with the shunt field-magnet winding is controlled by a relay that is energized in accordance with the voltage drop across both the accelerating and the dynamic-braking resistors. The relay may be provided with a coil connected across both the accelerating and the dynamic-braking resistors or with separate coils that are respectively connected across these two resistors. A strongly excited field is thus provided during both the accelerating and the dynamic-braking periods.

In the accompanying drawings, Figure 1 is a diagrammatic view of circuits and apparatus embodying my invention as applied to a unidirectional, compound-wound motor; Fig. 2 is a similar view of my invention as applied to a reversing motor; Fig. 3 is a schematic view of the system of Fig. 2, and Fig. 4 is a schematic view of a modification.

In the system of Fig. 1, a motor, having an armature 1, a shunt field-magnet winding 2 and a series field-magnet winding 3, is adapted to be supplied from any suitable source of energy by line conductors 4 and 5 and a line knife switch 6. An accelerating resistor 7 is connected in series with the armature 1 and is adapted to be short-circuited by a contactor 8 having a coil 9 that is adapted to be connected across the terminals of the armature. The circuit of the motor may be closed by a line contactor 10, having an actuating coil 11, the circuit of which may be closed by a start push-button switch and opened by a stop push-button

switch. A pair of switches 12 and 13 are mechanically connected to the contactor 10, the former of which creates a holding circuit, independent of the start push-button switch, for the coil 11 and controls the circuit of the coil 9, and the latter of which, the switch 13, is adapted to control a dynamic-braking circuit for the motor, comprising a dynamic-braking resistor 14 and a coil 15 for maintaining the contactor 10 open and the switch 13 closed. An overload relay 16 is provided with a coil 17.

In circuit with the shunt field-magnet winding 2 is a resistor 18 that is adapted to be short-circuited by a relay 19 having an actuating coil 20 that is connected across both the resistors 7 and 14 in series.

In operation, assuming that the line knife switch 6 is closed and that the start push-button switch is depressed, a circuit is established from the line conductor 4, through the knife switch 6, the coil 17, the overload relay 16, the start and stop push-button switches, the actuating coil 11, the series field-magnet winding 3 and the knife switch 6, to the line conductor 5. The contactor 10 is thereupon closed by its actuating coil 11 simultaneously with the closing of the switch 12 and the opening of the switch 13. The start push-button switch may be thereupon released, a holding circuit for the coil 11 being established from the line conductor 4, through the knife switch 6, the coil 17, the overload relay 16, the switch 12, the stop push-button switch, the coil 11, the series field-magnet winding 3 and the knife switch 6, to the line conductor 5. The contactor 10 will be maintained closed by its coil 11 until such time as the above-traced circuit is opened by the stop push-button switch or the overload relay 16.

The closing of the contactor 10 establishes the motor circuit from the line conductor 4, through the knife switch 6, the coil 17, the contactor 10, the armature 1, the accelerating resistor 7, the series field-magnet winding 3 and the knife switch 6, to the line conductor 5. The coil 20 becomes thereupon energized, in accordance with the voltage drop across the resistor 7 (the circuit, traced below, of the resistor 14 being open at the switch 13), thereby effecting the closing of the relay 19 to effect the short-circuiting of the resistor 18. The circuit of the shunt field-magnet winding 2 will now ex-

tend from the line conductor 4, through the knife switch 6, the coil 17, the relay 19, the shunt field-magnet winding 2 and the knife switch 6, to the line conductor 5. The shunt field-magnet winding 2 is thus strongly excited during the accelerating operation of the motor 1.

The coil 9 is connected across the armature 1 in a circuit extending from one brush 10 through the coil 9, the switch 12, the over-load relay 16, and the contactor 10, to the other brush of the armature 1. When the counter-electromotive force of the motor attains a predetermined value, therefore, the contactor 8 will be closed by its coil 9 to effect the short-circuiting of the resistor 7. The motor will then operate at a predetermined speed.

Upon the short-circuiting of the resistor 7, 20 the coil 20 becomes de-energized, effecting the opening of the relay 19 by gravity. The circuit of the shunt field-magnet winding 2 then extends from the line conductor 4, through the knife switch 6, the coil 17, the 25 resistor 18, the shunt field-magnet winding 2 and the knife switch 2, to the line conductor 5. That is, the resistor 18 becomes inserted into the circuit of the shunt field-magnet winding 2 to weaken the excitation 30 of this winding and to effect the operation of the motor at its maximum speed.

When it is desired to stop the motor, the stop push-button switch may be actuated to break the circuit of the coil 11. The contactor 10 thereupon drops open by gravity, effecting the opening also of the switch 12 and the closing of the switch 13. The motor then acts as generator, a dynamic-braking circuit being established from one brush of 35 the armature 1, through the switch 13, the coil 15, which aids gravity in maintaining the switch 13 closed, and the dynamic-braking resistor 14, to the other brush of the armature 1. The motor continues to act as a 40 generator until it comes approximately to rest. During all this time, the coil 20 is energized in accordance with the drop in voltage across the resistor 14, so that the relay 19 is maintained closed to effect the 45 short-circuiting of the resistor 18 and to provide for a strongly excited shunt field-magnet winding during the dynamic-braking 50 operation.

In accordance with my invention, therefore, the relay 19 is maintained closed during both the accelerating and the dynamic-braking operations to effect the short-circuiting of the resistor 18 and the consequent strong excitation of the field-magnet winding 2. The motor is thus provided with a 55 strongly excited field during both the accelerating and the dynamic-braking operations.

The system of Fig. 2 differs somewhat 60 from that of Fig. 1. As the motor of this

system is designed for operation in two directions, it is provided with not simply one contactor 10 but two, numbered 10 and 60, having actuating coils 11 and 61, respectively, and coils 15 and 65, respectively. 70 The contactors 10 and 60 are provided with mechanically connected contactors 12 and 62 and switches 13 and 63, respectively. The relay 19 is provided, in this instance, with two coils 20 and 70 that are respectively connected across the resistors 7 and 14. An additional master switch 71 is provided, having two positions in each of two opposite directions of operation, in one of which it controls the coil 11 and a coil 72, of an additional line contactor 73, and in the other of which it controls the coils 61 and 72. A switch 74 is mechanically connected to the line contactor 73 and controls the circuit of the counter-electromotive force coil 9. The 80 resistor 7 is adapted to be short-circuited in two steps, one of which is controlled by a contactor 75 having a series coil 76. This contactor and its coil are omitted from the system of Fig. 1 in order to simplify the 85 drawings of that system. The master switch 71 is connected to the line conductor 4.

Upon the actuation of the master switch 71 to its first position toward the left, a circuit is established from the line conductor 4, 95 through the master switch 71, the coil 11 and the knife switch 6, to the line conductor 5. The contactors 10 and 12 are thereupon closed, and the switch 13 is thereupon opened by the coil 11. The circuit of the 100 motor is, nevertheless, maintained open at the contactor 73. Upon the master switch 71 being actuated to its second position toward the left, a circuit becomes established from the line conductor 4, through the master 105 switch 71, the coil 72 and the knife switch 6, to the line conductor 5.

The motor circuit then extends from the line conductor 4, through the contactor 10, the armature 1, the switch 12, the coil 76, the 110 resistor 7, the series field-magnet winding 3, the line contactor 73 and the knife switch 6, to the line conductor 5. The coil 20, becoming energized by the drop in voltage across the resistor 7, the relay 19 becomes 115 closed to effect the short-circuiting of the resistor 18. The circuit of the shunt field-magnet winding 2, accordingly, extends from the line conductor 4, through the relay 19, the shunt field-magnet winding 2 and 120 the knife switch 6, to the line conductor 5. The shunt field-magnet winding 2 is thus strongly energized during the accelerating operation.

The contactor 75, which is preferably of 125 the lockout type, will become closed by its coil 76 upon the motor current dropping to a predetermined value to effect the short-circuiting of a portion of the resistor 7. After a time, when the counter-electro- 130

motive force attains a predetermined value, the coil 9 will effect the closing of the contactor 8 to affect the short-circuiting of the remaining portion of the resistor 7. The circuit of the coil 9 extends from one terminal of the armature 1 through the contactor 10, the switch 24, the coil 9 and the switch 63 to the other terminal of the armature 1.

Upon the short-circuiting of the entire 10 resistor 7, the coil 20 becomes de-energized, effecting the opening of the relay 19 by gravity and the consequent reinsertion of the resistor 18 into the shunt field-magnet-winding circuit. The motor will thereupon 15 operate at maximum speed.

To stop the motor, the master switch 71 may be returned to its initial illustrated position. This will have the effect of opening the control circuits, so that the motor 20 will become disconnected from the line conductors 4 and 5. Simultaneously with the opening of the contactor 10, the switch 13 will become closed, so that a dynamic-braking circuit will be established for the 25 motor which will extend from one brush of the armature 1 through the switch 13, the coil 15, the resistor 14, the coil 65 and the switch 63, to the other brush of the armature 1. The resistor 14, becoming thus 30 energized, the coil 70, which is connected across its terminals, will effect the closing of the relay 19 and the consequent short-circuiting of the resistor 18 in order to permit of the field-magnet winding 2 being 35 strongly excited. A strong field is thus provided for the motor during dynamic braking.

To operate the motor in the reverse direction, the master switch 71 may be 40 actuated to the right. The coil 61 will become energized to effect the closing of the contactors 60 and 62, which will establish the motor circuit for operation in the reverse direction. The operation is substantially the same as that described above in 45 connection with the description of the operation following upon the closing of the contactors 10 and 12. The coil 20 is connected across the resistor 7 to maintain the relay 50 19 closed during acceleration, and the coil 70 operates, during dynamic-braking, to effect a similar result during braking.

The circuits of Fig. 2 are schematically 55 shown in Fig. 3. It will be noted that the reason for employing two coils 20 and 70 instead of a single coil 20, as in the system of Fig. 1, is that the contactors 12 and 60 65 70 are connected in circuit between the armature 1 and the resistor 7. If the resistor 7 be permanently connected to the armature

1, and if the resistor 14 be connected between the two, as in Fig. 4, a single coil 20 may be employed, as in the case of the system of Fig. 1. In the system of Fig. 4, the contactors 10 and 12 and the switch 13 65 are mechanically connected, as in the system of Fig. 2. The contactors 60 and 62 are also mechanically connected but the switch 63 is omitted. If the switch 63 were not omitted, it would be necessary to employ 70 two coils 20 and 70, as in the system of Fig. 2.

Although I have shown several systems embodying my invention, it will be clear that the invention is not restricted thereto 75 and I desire that it be construed broadly, as defined in the appended claims.

I claim as my invention:

1. The combination with an electric motor having a pair of accelerating resistors and 80 a dynamic-braking resistor, of means responsive to the drop in potential across one of said accelerating resistors and said dynamic-braking resistor for controlling the other of said accelerating resistors. 85

2. The combination with an electric motor having armature and field-magnet windings, resistors in series therewith and a resistor in parallel to said armature winding, of a switch for controlling said field 90 resistor having an energizing coil connected across said other resistors.

3. The combination with an electric motor having armature and field-magnet windings, resistors in series therewith and 95 a resistor in parallel to said armature winding, of a switch for controlling said field resistor having an energizing coil responsive to the drop in potential connected across said parallel connected resistor.

4. The combination with an electric motor having armature and shunt field-magnet windings, resistors in series therewith, a resistor in parallel to said armature winding, said parallel-connected resistor 105 and said series-connected armature resistor being permanently connected together, a source of energy for said motor, and a pair of switches for connecting said motor to said source, of a switch for connecting said parallel-connected resistor in circuit with said armature, and a switch for short-circuiting said field resistor having an actuating coil connected across said parallel-connected and said armature resistors. 110

In testimony whereof, I have hereunto 115 subscribed my name this 23d day of April 1919.

ALBERT L. HARVEY.
